UNITED STATES PATENT OFFICE

1,978,921

PLANT PROTECTOR

Robert A. Wade, Paces, Va.

Application June 13, 1934, Serial No. 730,394

1 Claim. (Cl. 47—28)

My invention relates to new and useful improvements in plant protectors, and its object is to admit air and sunshine to growing plants and at the same time protect them from cold 5 weather, frost, wind, hail, rain, the hot dry sun and dry weather—from rodents, rabbits, bugs, beetles and insects of all kinds which attack plants and vegetables.

A further object of my invention consists in 10 its economical construction, durability, shape and arrangement, which render it inexpensive, efficient, easily transported, easy to set in place, easy to remove and easy to store away for future use from season to season. The protectors 15 will be made so that one can be nested in another when not in use and thus require the least storage space.

A further object of my invention is to make 20 the supporting wire frame so that it can be completely covered with a single piece of cloth without the necessity of sewing the cloth covering in any way in order to get the cloth to fit snugly over the wire frame, making a bug and beetle proof protector with the minimum waste 25 of cloth. This object is obtained by splitting the cloth covering at its corners and points of contact with the legs of the protector and using the legs as supports for fastening the cloth covering and stretching it rigidly over the wire 30 frame. The split ends of the cloth are used for fastening the cloth to the legs. Any porous cloth can be used and when stretched over the wire frame will admit the air and sunshine to the plant.

35 A further object of my invention consists in the ease with which the cloth covering can be put on and adjusted to the wire frame and then removed when desired for replacement purposes.

40 With the above and other objects in view the invention consists in the details of construction and in the arrangement and combination of parts to be hereinafter more fully described and particularly pointed out in the appended claim.

45 In describing the invention in detail reference will be made to the accompanying drawing forming part of this specification and in which drawing:—

Figure 1 is an elevation of the device showing 50 the improved plant protector embodying my invention.

Figure 2 is a bottom view of the device showing 55 how the cloth covering is fastened to the legs and also showing how the cloth covering fits on and around the wire base.

Figure 3 is a view showing the protector in place over a plant with the legs shoved into the ground up to the wire base making the protector bug proof.

Figure 4 is a view showing how the cloth covering is cut and split in order to fit snugly over the wire frame with the minimum waste of cloth.

In the drawing, wherein like reference characters designate corresponding parts throughout the several views, the letter A may generally designate the wire supports for the cloth covering, B the wire base, C the wire legs, E the cloth covering, Y the split ends of the cloth covering, Z the cloth flange around the bottom of the 70 protector.

The wires would ordinarily be spot welded to each other at their points of contact in order to secure a rigid frame, but it is not intended to limit the invention to this method of fastening the wire frame together.

The supporting wires A extend below the wire base B to form the legs C.

The legs C form the supports for fastening the cloth covering E over the supports A and 80 around and under the wire base B as shown in Figure 2.

The cloth covering E is split at its corners as shown in Figure 4. The split ends Y of the cloth covering E are used for fastening the cloth covering to and around the legs C as shown in Figure 2. The method of fastening shown in Figure 2 is that of tying what is commonly known as a hard knot with the split ends of the cloth covering but it is not intended to limit the method of fastening the cloth covering to and about the legs by this particular method of fastening.

When the split cloth covering is drawn around the legs and tied as illustrated in Figure 2, the tying of the split ends of the cloth, gathers, draws and stretches the cloth covering rigidly over, around and under the wire frame. The cloth covering fastened on in this manner forms a cloth flange about the wire base as shown in Figure 2. This cloth flange is designated in Figure 2 by the letter Z. The cloth flange makes a continuous contact with the ground when the protector is placed over a plant and the legs shoved into the ground up to the cloth flange containing the wire base.

I am aware that prior to my invention plant protectors have been made with wire frames and cloth covering, and I, therefore, do not claim such a combination broadly; but

I claim:

A plant protector comprising a wire base with supporting cross wires attached to the wire base and to each other in such manner as to give the protector the necessary shape and strength to support a cloth covering; the supporting cross wires extending below the wire base forming legs; the legs serving to anchor the protector in the ground and also serving as posts for

10

stretching the cloth covering rigidly over and around the wire frame; and also comprising a cloth covering split in such manner that when drawn down under and stretched around and under the wire base and frame and fastened to the legs makes a protector which will admit air and sunshine to a plant and at the same time protect the plant from bugs and other enemies.
